INVENTOR.
Fred R. Barbour
BY *Stewart K. Mack*
ATTORNEY.

UNITED STATES PATENT OFFICE.

FRED R. BARBOUR, OF LOS ANGELES, CALIFORNIA.

TENT.

Application filed August 21, 1924. Serial No. 733,373.

To all whom it may concern:

Be it known that I, FRED R. BARBOUR, a citizen of the United States, and a resident of Los Angeles, in the county of Los Angeles and State of California, have invented new and useful Improvements in Tents, of which the following is a specification.

This invention relates in general to tents, and more particularly to an improved type of tent capable of being readily and quickly assembled and erected for use, and of being folded into a compact roll or package when not in use, so that it may be carried about from place to place.

Other and more detailed objects of invention will appear as the description progresses.

I have shown in the accompanying drawings a preferred form of my invention, in which:

Fig. 1 is a perspective view, as seen from the front.

Fig. 2 is a fragmentary perspective view as seen from the side or rear.

Fig. 3 is a top plan view.

Fig. 4 is a fragmentary perspective, in section, showing the arrangement of the tent at the door.

Fig. 5 is a fragmentary section of the same, showing the manner of securing the tent to the ground; and

Fig. 6 is a composite view, in perspective, showing the arrangement of the supports at the top.

The tent as shown and herein described, embodies numerous details of structure heretofore used, together with other details of my own invention, which combine together to produce a satisfactory economical and convenient tent structure embodying but few parts, which I will clearly describe.

The tent as shown includes a top T, sides S, S, a front portion F, a rear portion R, and a floor f, composed of the usual strips of material sewed together and providing an integral tent structure. A door D is provided in the front, and one or more windows as at W may be provided in the sides or rear of the tent, as may be desired.

The door has a flap d which is secured at the top of the door to the front F, and is adapted to cover the door opening D and may be secured to the front F at a plurality of points by means of buttons b, b, etc., or otherwise. The door flap d may also be provided with straps as at e, e, by

means of which the same may be rolled and held upwardly, as shown in Fig. 1.

The window W has a flap W adapted to cover the same, which may be opened and closed by means of a suitable cord or strap g capable of being operated from the interior of the tent or otherwise.

The bottom of the tent may be provided with a cord as at C, suitably sewed into the tent material and extending entirely around the four sides of the tent, and said cord may be formed into loops as at L, L, etc., and extended outwardly at a plurality of points around the bottom of the tent and arranged to receive stakes as at 1, 1, etc., which may be driven into the ground for holding the tent firmly on the ground.

In the erection of the tent, the tent is first placed on the ground and stretched so that the bottom thereof will form a perfect rectangle or square, as the case may be, and the four corners are then staked to the ground as shown in Fig. 5. Thereafter, other of the stakes 1 are driven into the ground through the loops L at intermediate points, and at a sufficient number of points to hold the tent firmly down on the ground.

The top of the tent T is provided on the interior thereof and across the front and rear portions with open seams 2, 2, which are cut away at points 3, 3 in the center, and in which are held transverse metallic or wooden bars of round cross section, as at B, B, and longitudinally of the tent I provide a main cross bar B' which is provided with metallic hooks h, h, riveted or screwed to the member B' and provided with hook portions h', h' which are open at their upper sides and adapted to engage and receive the bars B, B in the seam openings 3, 3 in the center of the tent.

The entire tent, after having been secured to the ground as shown and described, may be held upwardly in the position shown in Fig. 1, and sufficiently taut for all ordinary purposes, by means of a single pole P which may be of solid or hollow material and formed of a pair or more of sections as at 4, 4, which are mitered at 5, 5, at their mating ends, and the mitered joint is adapted to be covered by a sleeve 6, as shown in Fig. 6.

Said sleeve may be attached to one or the other of the sections, or it may be loosely slidable on the upper section and limited

in its downward movement over the lower section by means of the pin 7 attached to the lower section, this arrangement being immaterial, except as to the provision of the 5 sleeve over the mitered joint.

The upper end of the upper section is provided with a bore 8 which is adapted to receive a pin 9 secured in and depending from the center of the main cross bar B'.

10 Thus, when the two sections 4, 4 of the pole P are attached together as shown in Fig. 1, and the joint therebetween covered by the sleeve 6, said pole may be moved under the bar B' into engagement with the pin 9 therein, until a vertical position is attained, which will stretch the tent material of the top, front, rear and sides into the position shown in Fig. 1 and hold the entire structure erect.

The transverse bars B, B are preferably 20 of steel or other metal and should be flexible enough so that when the pole P is moved into supporting position the members B, B and the top T will be slightly bowed as indicated in the drawings, for the purpose 25 of shedding water from the top of the tent.

When the tent is dis-assembled the pole P is first removed, and thereafter the bar B' is disengaged from the bars B, B and removed, whereupon the tent will collapse on 30 the ground and before the stakes 1, 1 are removed the tent may be jerked forwardly and thence rearwardly, and thence laterally from each side in turn, for straightening 35 out the folds of the tent and then folded and rolled into a relatively small package for rendering the same portable without removing the bars B, B.

The tent may or may not be provided with the floor f but when so provided the front 40 F is arranged at the door D with a narrow strip 9' extending above the level of the floor and disconnected therefrom at its bottom edge, and the floor f is provided with a flap 10 which is secured to the floor and 45 extends upwardly on the outside of and is adapted to be buttoned or otherwise removably attached to the strip 9' by means of the buttons b, b, or otherwise, so that the interior of the tent may be cleaned and the 50 refuse swept out under the bottom of the flap 9.

What I claim is:

1. A tent structure embodying a tent having a plurality of sides secured together, and a flat top secured to said sides, seams provided on the interior of the tent at the junction between the front and rear portions and the top portion thereof, said seams having alined openings therein in the center of the tent, bars held in said seams and exposed at said openings, a cross bar disposed at right angles to said first mentioned bars and having portions underlying the portions of said first mentioned bars at the openings of said seams, and a center pole 55 engaging said cross bar in the center of the tent and extending to the ground, for the purpose described.

2. A tent structure embodying a tent having a plurality of sides secured together, and a flat top secured to said sides, seams provided on the interior of the tent at the junction between the front and rear portions and the top portion thereof, said seams having alined openings therein in the center of the tent, bars held in said seams and exposed at said openings, a cross bar disposed at right angles to said first mentioned bars and having portions underlying the portions of said first mentioned bars at the openings of said seams, and a center pole 60 engaging said cross bar in the center of the tent and extending to the ground, said cross bar and said pole being removable for collapsing the tent.

3. A tent structure embodying a tent having a plurality of sides secured together, and a flat top secured to said sides, seams provided on the interior of the tent at the junction between the front and rear portions and the top portion thereof, said seams having alined openings therein in the center of the tent, bars held in said seams and exposed at said openings, a cross bar disposed at right angles to said first mentioned bars and having portions underlying the portions of said first mentioned bars at the openings of said seams, and a center pole 65 engaging said cross bar in the center of the tent and extending to the ground, said cross bar and said pole being removable for collapsing the tent, and said pole being formed in sections, as described.

4. A tent structure of the character described embodying a tent having a flat top with a pair of transversely disposed seams on the interior thereof, a pair of flexible bars carried in said seams, a longitudinally disposed bar having hooks on the end thereof engaging the lower sides of said transverse bars, and a sectional pole supported on the ground and removably connected with said longitudinal bar, said bars and said pole forming a frame for supporting said tent in position for use.

5. A tent frame including a pair of parallel and transversely disposed flexible bars, a longitudinally disposed bar having metallic hooks on the ends thereof, open at their upper sides and engaging the lower sides of said transverse bars, as described.

6. A tent frame including a pair of parallel and transversely disposed flexible bars, a longitudinally disposed bar having metallic hooks on the ends thereof, open at their upper sides and engaging the lower sides of said transverse bars, and a pole removably attached to said longitudinal bar and adapted to rest on the ground for holding said frame in position for use.

7. A tent frame including a pair of parallel and transversely disposed flexible bars, a longitudinally disposed bar having metallic hooks on the ends thereof, open at their upper sides and engaging the lower sides of said transverse bars, and a pole removably attached to said longitudinal bar and adapted to rest on the ground for holding said frame in position for use, said pole being formed in sections removably held together.
